GAS-FRACTIONATING SYSTEM

Johannes van der Ster, Emmasingel, Eindhoven, Netherlands, assignor, by mesne assignments, to North American Philips Company, Inc., New York, N.Y., a corporation of Delaware

Application October 27, 1955, Serial No. 543,218

Claims priority, application Netherlands March 30, 1955

10 Claims. (Cl. 62—40)

This invention relates to gas-fractionating systems comprising a gas-fractionating column and a boiler, in which a high-boiling fraction at least partially evaporates, and furthermore comprising a source of cold to condense the low-boiling fraction, the condensed liquid being partially supplied as washing liquid to the column and another part being drawn off from the system, whilst the column is connected with the boiler through a conduit which serves for the supply of liquid and extends into the liquid inside the boiler.

With gas-fractionating systems it has been proposed to regulate the amount of thermal energy supplied to a rise pipe, through which vapour is constantly bubbled for pumping up washing liquid, in accordance with the level of the liquid inside the boiler. Said regulation is effected in such manner that if the level inside the boiler rises less washing liquid is supplied to the column whereas the amount of washing liquid increases when the level drops. This may, for example, be effected by supplying the thermal energy, which is required for maintaining the vapour-bubble pumping action, with the aid of a metal element to the rise pipe, one end of said element being secured to the rise pipe and its other end being secured to a part of the system, thus transferring thermal energy through said element to the rise pipe. In the case of an excessive rise of the level inside the boiler said element is locally cooled by providing an overflow, so that less thermal energy is supplied to the rise pipe.

The invention likewise aims at regulating, in accordance with the level of the liquid inside the boiler, of the amount of washing liquid supplied to the column. However, the solution in accordance with the present invention is different.

In accordance with the invention two further conduits are provided between the boiler and the column to carry vapour back to the column, means being provided for closing one of said conduits upon a rise of the level of the liquid in the boiler, while cold is locally supplied to said conduit, the amount of said flow of heat determining the quantity of washing liquid supplied to the column. Hence, the rate of flow of heat determines the quantity of washing liquid in the column.

The means for closing the conduit may, for example, comprise a float controlled valve.

In one advantageous form, however, one of the conduits opens into the boiler at a lower point than does the other conduit and the conduit opening at a lower point into the boiler is closed by liquid upon a rise of the level of the liquid in the boiler.

Regulation may be effected in many different ways by means of said flow of cold. For example, the concentration of the fraction of high boiling point and of low boiling point inside the conduit may be used as an impetus for a control device. The concentration can be measured in known manner. In the case of fractionating air, for example, by means of a magnetic oxygen meter.

Alternatively, a suitable temperature may be used as an impetus for a control device. In one embodiment of the invention, the temperature at the wall where condensation occurs, which wall pertains to the conduit opening out at a lower point into the boiler, determines the amount of washing liquid through a control mechanism.

In another embodiment, the temperature inside the conduit opening into the boiler at a lower point determines the amount of washing liquid through a control mechanism. In this case, consequently, the temperature is measured in the space of the conduit. The temperatures may be measured in many different ways, for example with the aid of a thermo-element or a resistance thermometer. In a further embodiment of the invention, however, the driving force for the control mechanism is delivered by a vapour pressure thermometer, which itself produces the force required for the control.

The quantity of washing liquid supplied to the column is regulable in various ways by the temperature measuring devices. Thus, for example, a control cock may be provided in the conduit between the source of cold producing the washing liquid and the column. Alternatively, the washing liquid may be supplied to the column through a rise pipe in which a vapour bubble pumping action is maintained by heating electrically and the temperature regulates the degree of heating.

When using a vapour pressure thermometer and if the gas-fractionating system is used for fractionating air then oxygen, nitrogen or air may be used as vapour in the thermometer.

Regulation may be effected not only by temperature but also by the flow of cold.

This may be effected, in accordance with a further embodiment of the invention, in a system in which washing liquid is supplied to the column through a rise pipe through which vapour is bubbled to maintain a pumping action and which pipe is in heat-exchanging contact with the conduit opening into the boiler. In accordance with a suitable embodiment of the invention, in a system comprising a second rise pipe in which an air bubble pumping action is maintained for carrying a part of the condensed liquid off from the system and which pipe has the same down pipe as the first-mentioned rise pipe, the second rise pipe is in heat-exchanging contact with the vapour conduit opening into the boiler at a higher point. As a matter of fact, it may be advisable for the condensed liquid, which is drawn off from the system, to be pumped to a given height so that the outlet is at a higher point, which permits receptacles to be easily placed below the outlet.

As a result of the heat-transfer between the conduit and the rise tube, at least part of the vapour of the high boiling point will condense. In a further embodiment of the invention, the conduit opening into the boiler at a lower point advantageously comprises not only a rising part but also a down part, cold being supplied locally to the latter so that the vapour and the liquid flow in the same direction. The second conduit may also comprise such a down portion.

In order to carry off the condensed liquid from the conduit in a further embodiment of the invention, a down-part of a conduit comprises an outlet conduit for the condensed liquid produced in said parts, through which outlet conduit said condensed liquid is carried back to the boiler. In a further embodiment of the invention, said outlet conduit should extend into the liquid inside the boiler.

In a further embodiment of the invention, a satisfactory regulation is ensured by shaping the end of the conduit opening at a lower point into the column in such

manner that it is gradually closed if the liquid rises in the boiler.

The end of the conduit is preferably cut at an oblique angle in order to ensure the required gradual closure of the conduit in a simple manner.

In order that the invention may be readily carried into effect it will now be described in detail, by way of example, with reference to the accompanying drawings, in which

Figs. 1 and 2 show a gas-fractionating system, in which the conduits comprise both a rising part and a down part, Fig. 2 being a cross-sectional view on the line II-II of Fig. 1.

In Figs. 3 and 4 the conduits only have a rising part, part of the condensate produced by a gas-refrigerator being carried off from the system through a down pipe.

Fig. 4 is a cross-sectional view on the line IV-IV of Fig. 3.

In Fig. 5, the conduit opening at said lower point into the boiler comprises a vapour pressure thermometer with the aid of which the amount of condensed liquid supplied to the column is determined.

In Fig. 6 a space contains a cooling medium which is in heat-exchanging contact with the conduit opening at said lower point into the boiler.

Fig. 7 shows a gas refrigerator.

The system shown in Figs. 1 and 2 comprises a gas-fractionating column 1 comprising in known manner a filler, for example "Raschig" rings. The system furthermore comprises a boiler 2, wherein the high-boiling fraction evaporates. Between the column 1 and the boiler 2 is provided a partition 3 through which passes a conduit 4 which extends into the liquid inside the boiler. The boiler furthermore comprises an outlet pipe 5 which overtops the level of the liquid and passes through the bottom 6 of the boiler. This boiler is externally provided with fins 7 having openings 8 in such a manner that the openings of successive fins do not register. The fins are surrounded by a wall 9 with a supply conduit 10 and an outlet conduit 11. The conduit 11 opens into the column 1 at some distance from the bottom side. The column comprises an outlet conduit 12 for the low-boiling fraction, which outlet conduit is connected with a conduit 13 leading to the condenser space of a gas refrigerator 14. This gas refrigerator is of usual type and driven from an electric motor 15. Connected to the conduit 12 is a down pipe 16 with a receptacle 17 at its lower end, which receptacle carries two rise pipes 18 and 19. The rise pipe 18 opens into the column 1 at its upper end and the rise pipe 19 with an outlet conduit 19a for the produced vapour opens by way of a down part 20 and a liquid lock 21 outside the system.

The boiler 2 is connected with the column not only through the conduit 4 but also through two pipe connections 22 and 23. Besides the rising parts denoted by 22 and 23 said pipe connections also comprise down portions denoted by 24 and 25 respectively, which are coupled together through a conduit 26 and jointly open through a conduit 27 with a cock 28 into the column. The down parts 24 and 25 respectively comprise outlet conduits 29 and 30 respectively, which extend into the liquid of the boiler. The pipe connection 23 opens into the boiler at a point lower than does the pipe connection 22 and the mentioned pipe connection has its lower end cut at an oblique angle. The down-portion of the pipe connection 23 opening at a lower point into the boiler is in heat-exchanging contact with the rise pipe 18 through a conductive strip 32 while the down portion 24 of the pipe connection 22 is connected to the rise tube 19 through a conductive strip 33.

The system operates as follows:

On starting up the gas refrigerator, a subatmospheric pressure is produced in the condenser chamber of the gas refrigerator 14 and in the column 1 with the result that

the gas-mixture to be fractionated, hereinafter air is chosen, is drawn in through the conduit 10. The air flows through the heat-exchanger constituted by the tube 5 with fins 7 and is cooled in it due to the heat-exchanging contact of the tube 5 with the bottom 6 of the boiler 2. This boiler contains the high boiling fraction, in the present case oxygen, which evaporates due to the supply of thermal energy. Any impurities of the air, for example water vapour and carbonic acid, are frozen out in the heat exchanger. Such a heat exchanger is described in Belgian patent specification 527,602.

The air flows through the conduit 11 to the gas-fractionating column 1, in which it is fractionated in known manner. At the top of the column the low boiling fraction (nitrogen) is carried off in the gaseous state through the conduit 12, the nitrogen flowing through the conduit 13 to the gas refrigerator 14 and being condensed in its condenser chamber. The produced condensate leaves the refrigerator through the conduit 13 and flows into the down pipe 16 in which a fluid column forms. In the rise pipes 18 and 19 a vapour bubble pumping action is maintained by supplying thermal energy via elements 32 and 33 respectively, with the result that the condensed liquid is pumped up. The condensed liquid pumped up through the conduit 18 is supplied to the column and acts as a washing liquid in it. The other part of the condensate leaves the system through the conduit 20 and the liquid lock 21 and collects as a product in a receptacle (not shown). The high-boiling fraction, that is to say oxygen, produced in the column as a fluid through the pipe 4 into the column which invariably contains a certain quantity of liquid. Naturally, equilibrium has to be established between the amount of oxygen supplied from the column to the boiler 2 and the amount of oxygen evaporation due the supply of thermal energy through the air. This is achieved by using a system of particular construction comprising pipe connections 22 and 23. If the level of the liquid in the boiler is low, so that the pipe connection 23 opening into the boiler at a lower point protrudes from the level, a part of the produced vapour, which consists of an oxygen-nitrogen gas mixture rich in oxygen, will flow through the conduit 22, the down-part 24, the conduit 26 and the conduit 27 to the column 1. Another part of said gas mixture flows through the conduit 23, the down-portion 25, the conduit 26 and the conduit 27 likewise to the column. Since the temperature of said gas-mixture exceeds that of the nitrogen in the conduits 18 and 19 thermal energy will be supplied via strips 32 and 33 to the rise tubes 18 and 19 respectively, thus producing the aforesaid vapour bubble pumping action, that is to say a flow of cold occurs between said rise pipes 18 and 19, and the pipe connections 23 and 22 respectively. As a result of said flow of cold at least a part of the oxygen of the gas-mixture condenses and this condensate is carried back to the boiler through the conduits 29 and 30. The quantity of nitrogen supplied to the column through the rise pipe 18 is at least such that the level of the fluid in the boiler cannot drop far below the lower end of the conduit 23. If the liquid level rises in the boiler the conduit 23 is gradually closed on account of its end 31 cut at an oblique angle. As a result the concentration of oxygen inside the pipe connection 23 varies, since the gas mixture becomes poorer in oxygen and consequently richer in nitrogen, particularly if the pipe connection 23 is completely closed by the rising level of the fluid. Owing to the variation in concentration the flow of cold from the rise pipe 18 to the pipe connection 23 decreases, that is to say that the flow of thermal energy from the pipe connection to the rise pipe likewise decreases. As a result the vapour bubble pumping action decreases in the rise pipe 18, so that less nitrogen is supplied as washing liquid to the column and consequently less fluid rich in oxygen is supplied to the boiler, hence the liquid level again drops in the boiler. Naturally, oxy-

gen continues flowing through the conduit 22 to the column 1.

The cock 28 is adjusted in such manner that the pressure inside the boiler exceeds atmospheric pressure so that the oxygen vapour is partially blown off through the conduit 5 from the boiler and this oxygen co-acts in cooling the air supplied through the conduit 10. For a satisfactory operation of the aforesaid regulating device the temperature of the medium, which supplies the flow of cold to the pipe connection opening at a lower point into the boiler, should be as constant as possible. In the present case, this is ensured by the use of liquid nitrogen.

In the system shown in Figures 3 and 4, parts corresponding to those shown in Figures 1 and 2 are designated by the same reference numerals.

The air to be separated is supplied through a conduit 34 after discarding its impurities. In the heat exchanger 35, the air is cooled by the oxygen leaving the boiler through a conduit 36. Subsequently, the air flows through a helically wound heat-exchanger 37 inside the boiler 2 and is finally supplied to the column through the conduit 11. The produced nitrogen flows through the conduit 12 and the conduit 13 to the gas refrigerator 14 in which the nitrogen is condensed, the condensate subsequently being supplied through the conduit 13 to the down-pipe 16 and forming a column with a level 38 under normal operating conditions. Flush with said normal level, there is provided an outlet port 39 connected with an outlet pipe 40 comprising a liquid-lock 41. The down-pipe 16 leads to a container 17 with a rise pipe 18 which opens into the column. Similarly to Fig. 1, a vapour bubble pumping action is maintained in the rise pipe 18 and to this end thermal energy is supplied to the rise pipe by way of a strip 32.

The boiler has a wall 3 with a pipe 4 which extends into the liquid inside the boiler. The boiler is connected with the column through pipe connections 22 and 23 and conduits 26 and 27 with a cock 28. The pipe connection 23 opens into the boiler at a lower point than does the pipe connection 22 and the first-mentioned pipe connection is closed at its lower end. It is laterally furnished with a number of ports 42 situated above one another so that this conduit is gradually closed when the level of the liquid rises in the boiler. Through the strip 32 the pipe connection 23 is in heat-exchanging contact with the conduit 18. The operation of the system corresponds on the whole to that of the system shown in Figures 1 and 2.

If the level of the liquid rises in the boiler the pipe connection 23 is gradually closed so that, as has been stated above, the concentration of the gas-mixture in the pipe connection is changed and the flow of cold from the rise pipe to the pipe connection decreases and consequently also the flow of thermal energy to the rise pipe 18, hence the vapour bubble pumping action inside the pipe 18 decreases and less liquid is supplied to the column. As a result the level of the liquid in the down pipe 16 rises, so that a larger amount of liquid is carried off through the conduit 40 with the liquid lock 41. The outlet port 39 is situated at such a point that under normal operating conditions the desired amount of condensed liquid is carried off from the system.

The system shown in Fig. 5 substantially corresponds to the systems shown in Figures 1, 2 and 3, 4. Parts corresponding to those of preceding figures are designated by the same reference numerals. In the aforesaid constructions, the flow of cold itself provided for the control of the amount of washing liquid supplied to the column. Alternatively, other factors may provide for said control inter alia the aforesaid variation in gas-concentration in the pipe connection 23. In the following system the temperature is measured in the pipe connection and serves as an impetus to the control device.

The air to be fractionated flows through the conduit 10 to the heat-exchanger constituted by the pipe 5 with fins 7 and, due to its being cooled, gives off its impurities to said heat-exchanger, after which the purified and cooled air is supplied through the conduit 11 to the column. The gaseous nitrogen produced in the column flows through the conduit 12 to the gas refrigerator 14 and is condensed. The condensate flows through a conduit 43 with a branch pipe 44 and to a chamber 45 which is connected with the column through a number of ports 46. The conduit 44 is connected through a strip 32 to the pipe connection 23. The boiler furthermore comprises a pipe connection 22 which leads through a conduit 26 to the pipe connection 23 opening at a lower point into the boiler. Both pipe connections are connected with the column through a conduit 27 comprising a closure device (not shown). Into the chamber 45 extends a tube 47 with a liquid lock, which tube is pivotally connected at one end to a tube 48 arranged to be turned below the level of the liquid inside the chamber 45. Through a connecting rod system 50 the tube 48 is coupled to a plate 52 secured to bellows 51. The space 53 defined by the bellows and the plate 52 communicates through a port 54 with a chamber 55 which is in turn connected with a conduit 56 of a vapour pressure thermometer, the end 57 of which joins the pipe connection 23. The nitrogen in the conduit 44 serves as a source of cold for the pipe connection 23, the temperature of said nitrogen substantially being constant.

When the level of the liquid rises the pipe connection 23 is gradually closed, so that the temperature in said pipe connection decreases and the pressure in the vapour pressure thermometer drops off. This results in that the plate 52 descends and the oblique end of the pipe 48 descends further below the level of the liquid so that more liquid flows from the pipe 49 and is carried off from the system through the pipe 47. As a result less washing liquid is supplied to the column and consequently less liquid is supplied to the boiler, so that the liquid level in the boiler drops again. Besides by means of a vapour pressure thermometer the temperature inside the tube or the temperature of the condensed liquid may alternatively be measured with the aid of other temperature measuring devices such as, for example, thermo-elements or by means of a resistance thermometer. In these cases, a temperature variation may involve a variation of the amount of liquid supplied to the column.

In the system shown in Fig. 6 corresponding parts of preceding figures are designated by the same reference numerals. The air to be fractionated is again supplied through a conduit 10 and cooled by fins 7, the cooled air again flowing through the conduit 11 to the column 1. Nitrogen from the column flows through the conduit 12 to the gas refrigerator 14 and the liquid condensed therein is partially supplied through the conduit 43 to the chamber 45. The conduit 43 comprises a branch pipe 58 with a liquid lock 59 which is connected with a vessel 60 through a conduit 58. Through a strip 32 the vessel 60 is in heat-exchanging contact with the pipe connection 23 opening at a lower point into the boiler. The vessel 60 furthermore comprises an overflow pipe 61 with a liquid lock 62, which pipe is connected with a down-pipe 63 which in turn merges into a rise pipe 64. The vessel 60 furthermore comprises two vapour conduits 65 and 66, the conduit 65 comprising a cock 67 and being connected with the conduit 12, while the conduit 66 leads to the chamber 55, the vessel 60 thus being connected with the space 53 inside the bellows. A variation of the vapour pressure inside the vessel 60 consequently results in a displacement of the tube 48, similarly to the construction shown in Fig. 5. The rise

tube 64 opens into the conduit 43 and furthermore comprises a branch tube 65 opening into the conduit 12.

The pipe connections 22 and 23 for the supply of vapour from the boiler 2 to the column are not connected together, but open each individually into the column, the ports 68 and 69 having such a size that the pressure inside the boiler is sufficiently high to blow the remainder of the oxygen vapour through the pipe 5 off from the boiler, while the port 68 is larger than the port 69. The system operates as follows:

Owing to the cold supplied by the gas refrigerator the nitrogen leaving the column is condensed, the condensate being partially supplied as washing liquid through the conduit 43 and the chamber 45 to the column. The other part flows through the conduit 58 into the vessel 60 where this liquid produces a flow of cold to the pipe connection 23. The vapour produced in the vessel 60 is again supplied through the conduit 65 and the conduit 12 to the gas refrigerator, the pressure in the chamber 60 being transferred through the conduit 66 to the plate 52 of the bellows 54 with the result that the tube 48 assumes a given position.

When the liquid level rises in the boiler 2 the flow of cold from the vessel 60 to the pipe connection 23 decreases, as stated above with the result that less nitrogen evaporates in the vessel 60 and the pressure drops in this vessel. This results in that the pressure below the plate 52 likewise drops so that the tube 48 descends farther below the liquid level and more liquid is carried off from the system through the conduit 47. As long as the pipe connection 23 is closed a greater amount of gas naturally flows through the pipe connection 22 to the column.

Owing to lesser evaporation of nitrogen in the chamber 60 the liquid level increases in this chamber until the liquid is carried off from the vessel through the overflow pipe 61 and is supplied through the down-pipe 63 to the rise pipe 64. On account of unavoidable insulation losses, a vapour bubble pumping action may ensue in the rise tube 64 so that the nitrogen is pumped up and enters the conduit 43, the developed vapour being carried back to the gas-refrigerator 14 through the conduit 65a. Since a lesser amount of nitrogen is supplied to the column the liquid level inside the boiler 2 will again drop so that the conduit 23 is re-opened at its bottom end. The liquid locks 59 and 67 maintain the required pressure in the vessel 60, which pressure is adjusted by means of the cock 67.

The aforesaid systems comprise a gas-refrigerator for cooling the nitrogen from the column. The term gas-refrigerator is here to be understood to mean a so-called refrigerator operating according to the reversed hot-gas engine principle. Said refrigerators may be constructed in many different ways, for example as a displacer engine, a double-acting engine as an engine in which the cylinders comprising chamber of variable volumes subtend an angle, or as an engine in which the working chamber is combined with that of a hot-gas engine. A double-acting engine is described, for example, in U.S. Pat. No. 2,486,081.

The drawings represent a displacer engine which will be explained with reference to Fig. 7. The engine shown in this figure comprises a cylinder 70 in which a displacer 71 and a piston 78 are adapted to reciprocate harmonically with a substantially constant phase difference. To this end the displacer 71 is coupled through a connecting-rod system 73 to a crank of a crank-shaft 74, while the piston 72 is coupled through a connection-rod system 75 to cranks of the same crank-shaft. The space 76 above the displacer 71 is the so-called expansion chamber which communicates through a freezer 77, a regenerator 78, and a cooler 79 with a compression chamber 80 between the displacer and the piston. The refrigerator is driven from an electric motor 81

and as a result of the reciprocating motion of the displacer and the piston a gas, for example hydrogen or helium, in the engine performs a thermodynamic cycle so that cold is produced and another medium can be cooled by means of the freezer. For this purpose a condenser chamber 82 is provided, in which gas, for example the nitrogen from a gas-fractionating column, is condensed. Similarly to Figures 5 and 6, said nitrogen may be supplied through the conduit 12 to the condenser chamber 82 and drawn off as condensed liquid through the conduit 43.

In the systems as described hereinbefore it is naturally also possible to use other sources of cold, but these will considerably complicate the system in the majority of cases. As a matter of fact, the use of the gas-refrigerator permits the column to be constructed as a single column producing nitrogen of high purity, while the column is adapted to operate at atmospheric or substantially atmospheric pressure.

20 What is claimed is:

1. A gas fractionating system comprising a gas fractionating column, a boiler in which at least a part of the high boiling fraction evaporates, a source of cold to condense the low boiling fraction, transport means conveying a part of said condensed liquid as a washing liquid to said column and another part being carried off from said system, a first conduit connecting said column to said boiler and extending below the liquid level in said boiler, second and third conduits connected between the boiler and the column in order to transport vapor from the boiler to the column, said second and third conduits being in the form of an inverted U with one end adapted to be closed and opened by the rise and fall of liquid in the boiler and an outlet connecting said second and third conduits to said column, a third part of said condensed liquid being in heat exchanging relationship with at least one of the second and third conduits, and means whereby the quantity of heat delivered by the U to said transport means determines the 40 quantity of washing liquid delivered to the column.

2. A gas fractionating system comprising a gas fractionating column, a boiler in which at least a part of the high boiling fraction evaporates, a source of cold to condense the low boiling fraction, transport means conveying a part of said condensed liquid as a washing liquid to said column and another part being carried off from said system, a first conduit connecting said column to said boiler and extending below the liquid level in said boiler, second and third conduits connected between the boiler and the column in order to transport vapor from the boiler to the column, said second and third conduits being in the form of an inverted U with one end adapted to be closed and opened by the rise and fall of liquid in the boiler and an outlet connecting said second and third conduits to said column, a third part of said condensed liquid being in heat exchanging relationship with at least one of the second and third conduits, a condensation wall associated with said one end of the inverted U, and a control mechanism whereby 60 the quantity of heat delivered by the U to said transport means determines the quantity of washing liquid delivered to the column.

3. A gas fractionating system as claimed in claim 1 further comprising a control mechanism wherein the temperature in said one end of the inverted U determines the amount of washing liquid by means of said control mechanism.

4. A gas fractionating system as claimed in claim 2 further comprising a vapor pressure thermometer constituting the driving force for said control mechanism.

5. A gas fractionating system comprising a gas fractionating column, a boiler in which at least a part of the high boiling fraction evaporates, a source of cold to condense the low boiling fraction, transport means convey-

ing a part of said condensed liquid as a washing liquid to said column and another part being carried off from said system, a first conduit connecting said column to said boiler and extending below the liquid level in said boiler, second and third conduits connected between the boiler and the column in order to transport vapor from the boiler to the column, said second and third conduits being in the form of an inverted U with one end adapted to be closed and opened by the rise and fall of liquid in the boiler and an outlet connecting said second and third conduits to said column, a third part of said condensed liquid being in heat exchanging relationship with at least one of the second and third conduits, a substantially vertical pipe supplying washing liquid to the column by means of a vapor lift created by said heat exchanging relationship, and means whereby the quantity of heat delivered by the U to said transport means determines the quantity of washing liquid delivered to the column.

6. A gas fractionating system as claimed in claim 5 further comprising a second substantially vertical pipe wherein a vapor bubble pumping action occurs for carrying off a part of the condensed liquid from the system, said second vertical pipe being in heat exchanging contact with the other of said second and third conduits.

7. A gas fractionating system comprising a gas fractionating column, a boiler in which at least a part of the high boiling fraction evaporates, a source of cold to condense the low boiling fraction, transport means conveying a part of said condensed liquid as a washing liquid to said column and another part being carried off from said system, a first conduit connecting said column to said boiler and extending below the liquid level in said boiler, second and third conduits connected between the boiler and the column in order to transport vapor from the boiler to the column, said second and third conduits being in the form of an inverted U with one end adapted to be closed and opened by the rise and fall of liquid in the boiler and an outlet connecting said second and third conduits to said column, a third part of said condensed liquid being in heat exchanging relationship with at least one of the second and third conduits, means whereby the quantity of heat delivered by the U to said

transport means determines the quantity of washing liquid delivered to the column, and an outlet pipe between said second and third conduits wherein the condensed liquid produced in said system is conducted back to the boiler.

5. 8. A gas fractionating system as claimed in claim 1 further comprising an outlet pipe extending into the liquid inside the boiler and wherein said condensed liquid produced in said system is conducted back to said boiler.

9. A gas fractionating system comprising a gas fractionating column, a boiler in which at least a part of the

10 high boiling fraction evaporates, a source of cold to condense the low boiling fraction, transport means conveying a part of said condensed liquid as a washing liquid to said column and another part being carried off from said

15 system, a first conduit connecting said column to said boiler and extending below the liquid level in said boiler, second and third conduits connected between the boiler and the column in order to transport vapor from the

20 boiler to the column, said second and third conduits being in the form of an inverted U with one end adapted to be closed and opened by the rise and fall of liquid

25 in the boiler and an outlet connecting said second and third conduits to said column, said second conduit being so shaped so as to become gradually closed off when

30 the liquid rises in the boiler, a third part of said condensed liquid being in heat exchanging relationship with at least one of the second and third conduits, and means

35 whereby the quantity of heat delivered by the U to said transport means determines the quantity of washing liquid delivered to the column.

10. A gas fractionating system as claimed in claim 9 wherein said second conduit has one end cut off at an oblique angle.
